UNITED STATES PATENT OFFICE.

JOHN B. NAU, OF NEW YORK, N. Y.

ELECTRIC FURNACE.

990,765.

Specification of Letters Patent. Patented Apr. 25, 1911.

Application filed October 31, 1910. Serial No. 590,037.

To all whom it may concern:

Be it known that I, JOHN B. NAU, a citizen of the United States, and resident of New York city, in the county of New York and State of New York, have invented certain new and useful Electric Furnaces, of which the following is a specification.

This invention relates to an electric furnace more especially designed for the purpose of carrying out in an efficient manner my "process of purifying and refining iron" as per my application for Letters Patent Serial No. 518014 of September 16, 1909 allowed July 21, 1910 and issued February 21, 1911 under Patent No. 984590.

The nature of the present invention will be more fully understood from the following description, taken in connection with the accompanying drawings, forming part 20 thereof, in which:—

Figure I. is a plan view of the furnace; Fig. II. is a cross-section on line II.—II of Fig. I.; Fig. III. a cross section on line III.—III. of Fig. II.; Fig. IV. a cross section on line IV.—IV of Fig. II.

Referring to the drawings: It will be noticed that the complete apparatus constitutes an electric tilting furnace, resting by means of strong circular slides 1 fastened to the lower part of the furnace frame 9 on two parallel lines of rollers 2, carried in their turn by strong supports 3 only partly shown. The tilting of the furnace is obtained by any suitable tilting device, which owing to its style being immaterial for the understanding of this invention, is not shown on the drawings.

The furnace proper is mainly composed of two parts, of which one is a crucible 4, 40 surmounted by an ore shaft 5, open on top and preferably widening below, and the other one a fore-hearth 6 separated from crucible 4 by means of partition 7 and provided with an outlet pouring spout or opening 15 or other suitable pouring device. One or more openings 8 of convenient size and located in convenient places in the partition establish communication between crucible 4 and fore-hearth 6 for purposes hereinafter shown. Crucible 4 and fore-hearth 6 are inclosed in walls 16 of fire-bricks, inside the iron casing 9 of suitable shape. Ore shaft 5 also has preferably, but not neces-

sarily, a refractory lining inside an iron shell 10.

The electric current necessary for heating purposes in the furnace passes through electrodes 11 and 12 and may travel in any suitable direction. I have shown two sets of electrodes placed vertically, of which electrodes 11 of one set enter the crucible through its top and electrodes 12 of the other set enter the fore-hearth through its roof. The number of electrodes thus placed in one compartment may vary from one upward, their location also may vary, provided that the relative location remains such that the electric current going from one set to the other traverse the two compartments 4 and 6 and openings 8 in any desired direction.

Ore shaft 5 is provided furthermore with a liquid pig iron inlet 13 establishing communication between the inside of ore shaft 5 and inlet spout 14 suitably placed where shown on top of compartment 4. The center line of rotation of the furnace may be placed at any suitable height, but it is considered best to place it on or near the center line 13° of spout 14.

The operation in the furnace is as follows: After having heated the empty furnace in any manner such as, for instance, by burning gas introduced through pouring spout 15, the products of combustion passing through openings 8 to heat up crucible 4 before their escape through ore shaft 5, refining material in the shape of rich iron ore in solid pieces or in the shape of concentrate ore briquets is introduced into crucible 4 through ore shaft 5, until it fills up the crucible and ore shaft to any desired height. The ore may be introduced after having been heated previously, or it may be heated after its introduction by means of the heat derived from the burning of the gas in fore-hearth 6 or by other means.

After the ore is introduced, the liquid iron to be partly refined is poured from the liquid iron source into spout 14. Entering 100 the ore shaft through opening 13, it will fall on the heated iron ore, and being divided into small streams will percolate through the ore, gather on the bottom of compartments 4 and 6, its level will rise through the 105 mass of confined ore, and while refining will

take place rapidly, the slag forming on top of the iron in compartment 4 will rise to within easy reach of electrodes 11. The electric current, if not yet in operation, will be started and going in the direction of 11-12 for instance, will pass through slag and liquid iron, practically traverse the whole crucible or re-action zone, then through holes 8, it will rise through the iron bath in the fore-hearth and finally be received by electrodes 12. Thus, the electric current is made to heat up the slag as well as the iron in both compartments in the most efficient manner. The current, of course, may go in the other direction. In the course of the refining operation the ore immersed in the bath becoming consumed, the ore in the shaft will sink, and new supplies will have to be added on top while the refined iron will flow out through spout 15. Still, owing to the great buoyancy, the ore on top of the bath, in spite of the weight of the column of ore in the ore shaft, may not sink down into the bath as far as rapid refining will require. In that case, the furnace can be tilted, whereby the refined iron will be evacuated much faster than the raw iron can be introduced, and as soon as the furnace has been tilted to the dotted position 17, it will practically be empty of liquid iron. The ore contained in the shaft will descend to the bottom of the crucible and fill it. Tilting the furnace back again to its normal position, the ore shaft then can be filled up to the top if desired and the iron rising again in the crucible through the confined ore mass, will find an ample supply of it for refining purposes.

Holes or apertures 8 can be made large enough and located in the partition in such a manner, that when tilting the furnace to position 17, slag as well as iron will be evacuated completely through spout 15. This is of great advantage, because it affords not only easy means for evacuating the slag, but it makes it possible to pour this slag, which is of an excellent refining nature, and take it at once with the liquid iron from the purifier to the open hearth furnace to be used there in the final refining operation. Thus the slag itself will be a valuable product, that can be used at once to the best advantage in its liquid state.

Thus, the above-described tilting furnace realizes in a very practical manner the easy carrying out of my "process of purifying and refining iron" above-mentioned.

It is obvious that the manner of electrical heating herein described can be applied equally well to a stationary furnace having a crucible and a forehearth separated from each other by a partition or otherwise, but still communicating with each other through apertures similar to holes 8 in partition 7.

The location of the center line of rotation on or near line 13^a makes it possible to tilt

the furnace completely and empty it without stopping the inflow of the metal to be treated, since with the exception of the rotation around its center line, spout 14 remains in place. The uninterrupted continuity of the process is thereby assured.

The form of construction of both crucible and fore-hearth and their positions relatively to each other may be more or less varied from those specifically illustrated in the drawings, as will be obvious to those skilled in the art, without departing from my invention.

Referring to the drawings, it will be observed that the interior shape or conformation of the fore-hearth 6 is such that on tilting or oscillating the apparatus toward the right hand of Fig. IV the level of the bath in the fore-hearth will be caused to rise and a corresponding higher level consequently quickly communicated to the pool in crucible 4 by reason of some of the liquid contents of the fore-hearth quickly flowing back into the crucible 4 through the openings 8. This feature is of importance as it enables me, without substantial addition of molten material, to raise the level of the pool in the crucible 4 relatively to the entire body or aggregation of refining materials, thereby correspondingly increasing pressure from below upon super-disposed portions of said aggregation and also contact of the molten iron therewith, this tending to impart impulses to the refining materials, causing them to move to an extent relatively to each other, and thus assisting in producing new contacts between them and the molten iron and also in preparing them to move downward more certainly to positions required when the apparatus is tilted in the opposite direction, *i. e.* toward the left of Fig. IV, whereby the level of the liquid contents is lowered as hereinbefore described.

It will be noted that the same results will follow the tilting as described in cases in which the partition 7 is removed, thereby bringing into a single crucible the spaces occupied by fore-hearth 6, partition 7 and original crucible 4, as shown in Fig. II.

I claim as my invention:

1. In an apparatus for refining molten pig iron the combination of a movable hearth containing a crucible comprising a therefrom upwardly extending ore shaft opening thereinto, below the top of said shaft an inlet, and below said inlet and normally above the bottom of said crucible an outlet, and means to together oscillate said hearth and shaft simultaneously relatively to a common axis of rotation.

2. In an apparatus for refining molten pig iron the combination of a movable hearth containing a crucible comprising a therefrom upwardly extending ore shaft opening thereinto, below the top of said shaft an in-

let, and below said inlet and normally above the bottom of said crucible an outlet, means to together oscillate said hearth and shaft simultaneously relatively to a common axis 5 of rotation, and means for generating heat in said crucible independently of material therein charged.

3. In an apparatus for refining molten pig iron the combination of a movable hearth 10 containing a crucible comprising a therefrom upwardly extending downwardly flaring ore shaft opening thereinto, below the top of said shaft an inlet and normally above the bottom of said crucible an outlet, 15 and means to together oscillate said hearth and shaft simultaneously relatively to a common axis of rotation.

4. In an apparatus for refining molten pig iron the combination of a movable hearth 20 containing a crucible comprising a therefrom upwardly extending ore shaft of less diameter than said crucible and opening thereinto, below the top of said shaft an inlet, and below said inlet and normally above the bottom of said crucible an outlet, and means to together oscillate said hearth and shaft simultaneously relatively to a common axis of rotation.

5. In an apparatus for refining molten pig 30 iron the combination of a movable hearth containing a crucible comprising a therefrom upwardly extending ore shaft opening thereinto, means to together oscillate said hearth and shaft simultaneously relatively to a common axis, below the top of said shaft an inlet having its center located approximately on said axis, and below said inlet and normally above the bottom of said crucible an outlet.

40 6. In an apparatus for refining molten pig iron the combination of a movable hearth containing a crucible comprising a therefrom upwardly extending ore shaft opening thereinto, adjacent said crucible a fore-hearth separated therefrom by a partition containing a passage between said fore-hearth and crucible, below the top of said shaft an inlet, from said fore-hearth an outlet, and means to together oscillate said 45 hearth and shaft simultaneously relatively to a common axis of rotation.

7. In an apparatus for refining molten pig iron the combination of a movable hearth containing a crucible comprising a therefrom upwardly extending ore shaft opening thereinto, adjacent said crucible a fore-hearth separated therefrom by a partition containing a passage between said fore-hearth and crucible, below the top of said shaft an inlet, from said fore-hearth an outlet, means to together oscillate said hearth and shaft simultaneously relatively to a common axis of rotation, and means for generating heat in said crucible and in said fore-hearth.

65 8. In an apparatus for refining molten pig

iron the combination of a movable hearth containing a crucible comprising a therefrom upwardly extending ore shaft opening thereinto, adjacent said crucible a fore-hearth separated therefrom by a partition 70 containing a passage between said fore-hearth and crucible, below the top of said shaft an inlet, from said fore-hearth an outlet, and means to together oscillate said hearth and shaft simultaneously relatively to a common axis of rotation, disposed outside of said crucible and fore-hearth a source of electrical energy, in said crucible an electrode, in said fore-hearth another electrode, and conductors connecting said electrodes 80 with said source.

9. In an apparatus for refining molten pig iron the combination of a movable hearth having a container for said iron comprising a therefrom upwardly extending ore-shaft 85 opening thereinto, below the top of said shaft an inlet and below said inlet and normally above the bottom of said crucible an outlet, and means to together oscillate said hearth and shaft simultaneously relatively to a common axis of rotation, the interior shape and dimensions of said container being such as to cause the level of said iron to rise therein when oscillated in one direction and to fall when oscillated in the opposite 95 direction.

10. In an apparatus for refining molten pig iron the combination of a movable hearth containing a crucible comprising a therefrom upwardly extending ore-shaft opening thereinto, adjacent said crucible a fore-hearth separated therefrom by a partition containing a passage between said fore-hearth and crucible, below the top of said shaft an inlet, from said fore-hearth an outlet normally above the bottom of said crucible and fore-hearth, and means to together oscillate said hearth and shaft simultaneously relatively to a common axis of rotation, the interior shape and dimensions of said fore-hearth being such as to cause the level of said iron to rise in said fore-hearth and in said crucible when oscillated in one direction and to fall when oscillated in the opposite direction.

11. In an apparatus for refining molten pig iron the combination of a movable hearth having a container for said iron and means to oscillate said hearth, the interior shape and dimensions of said container being such as to cause the level of said iron to rise therein when oscillated in one direction and to fall when oscillated in the opposite direction.

12. In an apparatus for refining molten pig iron the combination of a movable hearth containing a crucible and adjacent said crucible a fore-hearth separated therefrom by a partition containing a passage between said fore-hearth and crucible, and means to
